UNITED STATES PATENT OFFICE.

ARCHIBALD J. TURNER, OF CHICAGO, ILLINOIS, ASSIGNOR TO WILSON-WESTERN SPORTING GOODS CO., OF CHICAGO, ILLINOIS, A CORPORATION OF DELAWARE.

INFLATABLE BALL.

Application filed March 19, 1927. Serial No. 176,604.

My invention relates to inflatable balls, being more particularly concerned with improvements in the disposition of lacing for the entrance slits in such balls.

5 In certain types of inflatable balls, notably basket balls, it is essential that there be nothing on the cover projecting beyond its normal spherical surface, which is liable to be caught in a basket frame or the like, or which may cause the directions of rebound of the ball to become uncertain or irregular. The old types of projecting lacings heretofore used on basket balls, have materially affected the rebound of such balls, 10 and have frequently become caught in basket frames or the like. Moreover, such projecting lacings tend to become worn by contact with the floor and other surfaces engaged by the ball in play, and interior or 15 concealed lacings have been provided to obviate this difficulty.

While the interior or concealed type of lacing has many advantages, it is not visible nor so readily accessible as the old type 20 of projecting lacing, and one of the objects of the present invention is the elimination of the foregoing difficulties by the provision of a visible and readily accessible lacing which is flush with the normal spherical 25 surface of the ball without altering the continuity of the leather or fabric on the outside of the casing adjacent said slit.

Another object of my invention is the provision of a ball having an entrance slit and 30 the lacing for the same together with spacing means disposed within the casing adjacent said slit in such manner that the exterior portions of the lacing may imbed themselves in the exterior surface of the cover 35 without injury to the same while that part of the cover between said portions of lacing is maintained by said spacing means in 40 its normal spherical shape.

Another object of my invention is the provision of spacing means of the class described, which is built up of a plurality of layers of flexible material so that this member may perform its function without materially stiffening that portion of the cover to 50 which it is affixed or deleteriously affecting the qualities of rebound in any way.

Other objects and advantages of my invention will appear more fully from the following description and from the accompanying drawings, in which similar characters of

reference indicate similar parts throughout the several views.

In the drawings:

Figure 1 is a plan view of a basket ball 60 embodying my invention;

Figure 2 is an enlarged detailed view of that portion of the cover adjacent the slit and lacing;

Figure 3 is a view in perspective of the spacing means employed in my invention;

Figure 4 is an enlarged cross sectional view taken on the line 4-4 of Figure 2;

Figure 5 is an enlarged cross sectional view taken on the line 5-5 of Figure 2;

Figure 6 is an enlarged cross sectional 70 view on the line 6-6 of Figure 2, and

Figure 7 is an enlarged view in perspective and in disassembled relation of the spacing means shown in Figure 3.

Referring to Figure 1, 10 indicates in its 75 entirety an inflatable ball which is provided with a lacing and entrance slit according to the present invention. While the improvements of the present invention are primarily intended to be applied to basket balls, and 80 other inflatable balls, it is contemplated that the advantages may also be realized in some measure in balls which are stuffed or which have their covers filled out by some means other than an inflated bladder, and I desire 85 it to be understood that I do not wish to be limited to the use set forth.

The ball 10 may be constructed in the usual manner, as in the present instance of a plurality of pieces of leather of high quality, which are stitched together in any convenient or suitable manner. As a general rule such a ball will have an entrance slit 90 11 centrally disposed upon one side of the ball between two adjacent pieces of leather 95 12 and 13. The slit 11 is conveniently formed by terminating the stitching which joins the leather pieces 12 and 13 at the point 14, one end of the slit and at the point 14 the opposite end of the slit, and in order 100 that the adjacent edges of the leather pieces may abut smoothly against each other along said slit, the excess of leather between the points 14 and 15 which would ordinarily be used to form the seam, is cut away until the 105 edges abut squarely against each other, forming the normal spherical surface of the ball when the slit is properly drawn together.

While the general structure of the en. 110

trance slit shown may be employed with any ordinary style or type of lacing; I prefer to use the style of lacing which is fully described in my copending application, Serial No. 112,427, filed by me May 29, 1926, now patent No. 1,621,043, granted March 15, 1927, as this is a style of lacing which provides a plurality of parallel two ply exterior laced portions indicated in the drawing at 15, and 10 a plurality of one ply interior laced portions 16 and 17 crossing each other diagonally, and maintaining the parallelism of the exterior two ply laced portions. When the ball is laced in this manner, the lacing has 15 no tendency to cause margins of the insertion openings to creep relative to each other, and the portions of the lace which lie outside of the cover are parallel to each other and at right angles to the margins of the 20 bladder insertion opening. This type of lacing has particular advantages when used in connection with the present entrance slit construction, as will be further explained.

In order that the exterior portions 15 of 25 the lacing may lie flush with the normal spherical surface of the cover, and in order to accomplish this result without cutting away any part of the cover adjacent the entrance slit, I provide means whereby the 30 exterior portions 15 of the lace may imbed themselves in the cover of the ball, as is shown in Figure 4. The means by which this result is accomplished comprises a plurality of spacing members which permit the 35 exterior lacing portions 15 to draw the cover downward to the point where these portions are located flush with the surface of the ball, but which maintains the balance of the cover between said lacing and elsewhere in its normal spherical shape.

A convenient form of such spacing means is shown in Figures 3 and 7 in which 18 indicates a piece of leather of good quality having an edge 19 which is adapted to be 40 aligned with the edge of one side of the slit 11 when the edges 20 are caught in with the regular seams of the ball beginning at the points 14 and 15. The leather piece 21 comprises a substantially rectangular piece 45 of leather of the relative thickness shown having a forward edge 22 which is adapted to be aligned with the edge 19 of the slit 11. The edge 22 has a plurality of cut-outs 23 at 50 regularly spaced intervals and located so that when the leather pieces are in assembled relation with the ball and lacing, the exterior portions 15 of the lacing will be centrally located above each of the cut-outs 23. The width of the cut-outs 23 should be 55 such that when the lacing is in the position shown in Figure 4, the material removed from these portions is sufficient to provide ample space for that portion of the cover and lining which is depressed into the cut-outs as at 24 and the depth of the cut-outs 60

should preferably be such that they extend beyond the hole on the side away from the slit as at 25, a distance which affords the same clearance about the lacing holes 26 as is provided on either side of the lacing.

The cut-outs 23 will thereby leave a plurality of projecting tongues 27 which are adapted to maintain the balance of the cover of the ball between the exterior lacing portions in its normal spherical shape, and it will be observed that as the last two exterior portions of lacing may be located just beyond the leather piece 21 at each end, only sufficient tongues 27 are provided as are necessary to lie between the exterior lacing portions.

The cover pieces 12 and 13 are each provided adjacent the slit 11 with a row of equally spaced apertures 26 and the apertures 26 are preferably located directly opposite each other so that when the lacing is in place, the exterior portions 15 will extend exactly at right angles to the slit 11. The leather piece 18 is likewise provided with a row of apertures 28 which are similarly spaced and adapted to be exactly aligned with the apertures 26 of the cover when these parts are in assembled relation.

The leather piece 29 comprises a piece of leather such as is ordinarily employed in constructing the cover having a forward edge 30 which is likewise adapted to coincide with the edge of the slit 11, and having a plurality of cut-outs 23 of a shape and size exactly similar to those of the leather piece 21, thereby forming a plurality of similar tongues 27. In order to gradually decrease the thickness of the spacing member toward its outer edge, the leather piece 29 may be beveled off at its exterior edge from the point 31 on one end around the back side 32 to a point 33 on the opposite end of the slit. The leather piece 29, in addition to having a number of cut-outs 23 equal to that of the piece 21, has an extra cut-out 34 located at each end of the slit and adapted to provide indentation space for the cover below the outermost portions of lacing 15, and the projecting corners 31 and 33 of the piece 29 are adapted to support the cover beyond such outermost portions of lacing to keep such part in normal spherical shape. It should be noted that at the points 33 and 31, or the points 14 and 14^a which are adjacent thereto, the normally inwardly turned edges of the pieces 12 and 13 at the seam provide adequate means for holding this part of the cover upward in spite of the groove or indentation formed by the exterior lacing in the outer cover at this point.

The leather piece 21 may be cemented upon the leather piece 18, with their edges 22 and 19 coinciding and the apertures 28 centrally located in all of the cut-outs 23. The piece 29 may then be superimposed upon

the piece 21 in such manner that the forward edge 30 coincides with the edges 19 and 22, and the cut-outs 23 of this piece coincide with the cut-outs of the piece 21, and all of these pieces having been firmly cemented together, a single line of stitching 35 may be made along each set of tongues 27 for the purpose of securing all of these parts together and forming the spacing means shown in Figure 3. In order that there may be no tendency to form bumps or angles at the rear side of the spacing means, the rear edge 36 of the leather piece 18, as well as each end 37, may also be given a long bevel so that the thickness of the spacing means gradually decreases toward its outer edge to a very small value. While the shape of the rearward portions of these parts is not of great importance, it should preferably be such that the thickness of the member may gradually decrease in all directions from the lacing in the manner described.

The leather pieces 12 and 13, as well as the other pieces which compose the cover of the ball, are preferably provided with a lining comprising at least two layers of closely woven and strong fabric, the said layers having the woof and warp so disposed that the cover is adapted to expand equally in all directions, and a spacing member 38 may be fixed upon each side of the slit 11 by cementing one of said spacing members to the lining 39, each having the holes 28 in alignment with the holes 26 and the combined edge 40 of the spacing member 38 aligned with the edge of the slit 11 on each side. The spacing member 38 may then be permanently attached to the cover of the ball by a line of stitching 41 beginning in the outermost cut-outs 34 and extending diagonally therefrom to a point 42, thence along a curved line to a similar point at the opposite end of the spacing member, thence diagonally inward toward the slit terminating in the other cutout 34.

Stitching so made will pass through both the layers 18 and 29 and in the layer 21. In order that this stitching, which should preferably be made with extra heavy thread, may not form any projection on the exterior surface of the ball, I provide in my spacing member means for permitting a slight depression of the surface of the seam on the exterior of the ball. The leather piece 29 is, therefore, preferably provided with a slot 43 extending from a point adjacent the point 33 along the line of the stitching described to a point adjacent the point 31, with the exception of a plurality of supporting strips 44. The supporting strips 44 which hold these parts of the leather piece 29 together, may also be rounded out slightly to make room for the seam. It will thus be observed that when the stitching 41 is made along the line described, firmly drawing these parts of

the spacing member and cover together, the slot 43 will provide a space wherein the lining 39 and the cover piece 12 or 13 may be drawn so that the upper edge 45 of the stitching lies in a slight depression of the cover as at 46 and is flush with the normal spherical surface of the ball.

By making the spacing member 38 of a plurality of plies of flexible leather, I am enabled to provide spacing means of the necessary thickness without appreciably affecting the resilient qualities of the ball at or near the slit, and by providing means whereby the exterior portions of the lacing can draw the cover downward into grooves to imbed themselves flush with the surface, I am enabled to keep the lacing flush with the surface of the ball without cutting away parts of the cover or otherwise destroying the continuity of the leather pieces forming the margins of the slit.

The ball may be provided with the usual protective flap of leather 47 comprising a substantially rectangular piece of leather having its outer edges thinned as at 48 and having one side secured to the cover by the same stitching 45 which secures the cover and spacing member 38. For the purpose of illustration, in Figures 4 to 6, the inward protrusion of the lacing portions 16 and 17 is slightly exaggerated, but when the ball is filled and these parts are under pressure, the flap 47 is adapted to substantially smooth out the irregularities caused inside of the cover by the lacing so as to protect the bladder therefrom.

Since the cut-outs 34 in the spacing member are made at right angles to the slit and since the exterior portions 15 of the lacing should be so located that they will be able to draw the cover and lining down into the cut-outs, it is of particular importance and advantage to use the type of lacing shown in my prior application above mentioned, because this lacing is especially adapted to maintain the exterior portions of the lacing 15 at right angles to the slit without causing the adjacent margins of the slit to creep or otherwise disturb the alignment of the apertures 26 or the cut-outs 34. The lacing employed may consist of a leather thong in which case the exterior portions 15 may consist of two plies one above the other, or the lacing may consist of a strong, closely woven cord of round cross section, as shown in Figure 2, in which case the exterior portions may be arranged as shown side by side each other. When a fabric lace is employed, its ends are preferably knotted together as indicated at 49, the knot being slipped down between the edges of the slit and disposed between the spacing member 38 and the flap 47.

I have not illustrated a bladder in the accompanying drawing, because the present invention is not concerned with any of the de-

tails of a bladder. The improvements of this invention may be applied to a ball of the type wherein a bladder is inflated after the closure of the insertion opening, or may be applied to a ball equipped with the old style bladder provided with a rubber inflation tube, which must be closed and tucked back inside the cover after the inflation of the bladder has been effected. The ball illustrated in Figure 1 is of the former type, having a bladder inflation stem opening and support carried by the rear side of the ball shown in this figure.

It will thus be observed that I have invented a ball having an entrance slit closed by lacing and so constructed that the lacing is adapted to lie flush with the normal spherical surface of the ball, the lacing imbedding itself in a plurality of bends in the leather adjacent said entrance slit. It will also be observed that I have provided means for accomplishing this result without cutting away portions of the cover adjacent said slit, or otherwise destroying the continuity of the leather pieces forming this portion of the cover, and that the spacing members employed are adapted to perform their function without materially stiffening the cover of the ball at this point as would be the case if rigid spacing members were employed.

While I have illustrated and described the specific embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A ball comprising an outer casing having an entrance slit, and a lacing for said slit disposed flush with the outer surface of said casing in grooves comprising bends in said casing.

2. A ball comprising an outer casing having an entrance slit, a lacing for said slit, and means for permitting said lacing to draw said casing inward at each exterior portion of said lacing until said lacing is flush with the major surface of said casing.

3. A ball comprising an outer casing formed with an entrance slit, spacing means having a plurality of transverse grooves therein, carried inside said slit, and a lacing for said slit, said lacing being disposed flush with the outer surface of said ball in said transverse grooves.

4. A ball comprising an outer casing formed with an entrance slit, spacing means having a plurality of transverse grooves therein disposed along the interior of said slit, said spacing means comprising a plurality of layers of flexible leather, and a lacing

for said slit, said lacing being disposed with its exterior portions and that part of the cover underneath them drawn into said transverse grooves, said exterior portions being flush with the normal spherical surface 70 of the casing.

5. A ball comprising an outer casing formed with an entrance slit, spacing means having a plurality of transverse grooves for receiving parts of the cover, said spacing means being disposed along the interior of said slit and being gradually thinner toward its edges away from said slit, and a lacing for said slit having its exterior portions drawn into said grooves flush with the normal spherical surface of the ball. 75

6. A ball comprising an outer casing having an entrance slit, a lacing for said slit, and means for supporting the parts of the cover adjacent the exterior portions of said lacing in their normal spherical shape while permitting said lacing to imbed itself in the cover at said exterior portions. 85

7. A ball comprising an outer casing having an entrance slit, spacing means carried within said casing along said slit for supporting a lacing flush with the normal spherical surface of the ball, said spacing means having a plurality of transverse slots at right angles to said slit, and a lacing for said slit comprising a plurality of double exterior portions imbedded in said cover and at right angles to said slit, and a plurality of diagonal portions inside said cover maintaining said exterior portions at right angles to said slit. 90

8. A ball cover comprising a casing having a slit, and means for closing said slit carried by said casing and disposed in grooves formed by bends in said casing. 105

9. In a device of the class described a casing having an opening, and means for securing edges of said casing adjacent said opening, in abutting relation, comprising securing means disposed in grooves formed by bends in said casing and substantially below the normal contour of said casing. 110

10. In a closure, the combination of a pair of abutting members having a plurality of points of engagement for securing means, a backing having a plurality of grooves extending below said members and between said points of engagement, and securing means for drawing said members together and embedding itself in grooves formed by drawing said casing into the grooves of said backing. 115

11. A playing ball closure comprising abutting edges of a leather casing, a leather backing member secured under each of said abutting edges, said casing having rows of apertures for a lacing and said backing members having aligned slots underneath the casing between pairs of apertures, and a lacing securing said edges together and em- 120

bedded in the outer surface of said casing.

12. A playing ball closure comprising abutting edges of a leather casing, a leather backing member secured under each of said abutting edges, said casing having rows of apertures for a lacing and said backing members having aligned slots underneath the casing between pairs of apertures, a support for said backing members comprising a pair of abutting pieces of leather formed with an outer edge tapering in thickness to eliminate abrupt changes in thickness of said casing, and a lacing securing said edges together and embedded in the outer surface of said casing.

13. A playing ball closure comprising abutting edges of a leather casing, a leather backing member secured under each of said abutting edges, said casing having rows of apertures for a lacing and said backing members having aligned slots underneath the casing between pairs of apertures, a support for said backing members comprising a pair of abutting pieces of leather formed with an outer edge tapering in thickness to eliminate abrupt changes in thickness of said casing, a lacing securing said edges together and embedded in the outer surface of said casing, and a protective flap of leather bridging the inside of abutting edges of said casing.

14. A playing ball closure comprising abutting edges of a leather casing, a leather backing member secured under each of said abutting edges, said casing having rows of apertures for a lacing and said backing members having aligned slots underneath the casing between pairs of apertures, a sup-

port for said backing members comprising a pair of abutting pieces of leather formed with an outer edge tapering in thickness to eliminate abrupt changes in thickness of said casing, and a lacing having pairs of lacing parts extending between pairs of opposite apertures outside said casing and parts of lacing crossed at intermediate points between the pairs of opposite apertures inside said casing.

15. In an inflatable ball a closure slit formed by pieces of leather sewed together from each end of said slit, backing means for said slit comprising leather pieces along said slit inside said casing, said leather pieces having a thinned edge and slots removed beneath the seam line about said closure slit, a support for said backing comprising leather pieces sewed to said backing and stitching through said support and casing about said closure.

16. In an inflatable ball a closure slit formed by pieces of leather sewed together from each end of said slit, backing means for said slit comprising leather pieces along said slit inside said casing, said leather pieces having a thinned edge and slots removed beneath the seam line about said closure slit, a support for said backing comprising leather pieces sewed to said backing and stitching through said support and casing about said closure, said support also having its edges caught in the stitching of said casing at each end of said slit.

In witness whereof, I hereunto subscribe my name this 16th day of March, 1927.

ARCHIBALD J. TURNER.
